CASE FOR A DATA COMMUNICATION TERMINAL

Donald L. Tripp, Mountain Lakes, N.J., assignor to
Computer Transceiver Systems, Inc., Upper Saddle
River, N.J., a corporation of New York

Filed Apr. 23, 1969, Ser. No. 16,864

Term of patent 14 years

Int. Cl. D20—02

U.S. Cl. D26—5

FIG. 2

FIG. 1

FIG. 3

FIG. 4

FIG. 1 is a perspective view of a case for a data communication terminal embodying my new design;

FIG. 2 is a side elevational view thereof;

FIG. 3 is a top plan view thereof; and

FIG. 4 is a front elevational view thereof.

I claim:

The ornamental design for a case for a data communication terminal, as shown.
